United States Patent [19]

Hoshino

[11] Patent Number: Des. 305,753

[45] Date of Patent:  Jan. 30, 1990

[54] COMPUTER

[76] Inventor: Nobuhiko Hoshino, Boardinghouse of Tokyo Sanyo, 1939-24 Shimokoizumi, Ohizumi-Cho, Ohra-Gun, Gunma-ken, Japan

[] Term: 14 Years

[21] Appl. No.: 910,761

[22] Filed: Sep. 23, 1986

[30] Foreign Application Priority Data

Mar. 28, 1986 [JP] Japan 61-11552

[52] U.S. Cl. D14/102

[58] Field of Search D14/100-117; D13/40, 41, 32, 24, 12, 4, 10, 13, 34; D18/1, 2, 5, 6, 7, 8, 11, 13; 360/97, 98, 99, 132, 133, 99.02; 361/330, 331, 332, 334, 335, 348, 352, 358, 379, 380, 381, 384, 390-395, 415, 426, 2, 4, 9; 312/299, 304, 208, 270, 275, 253; 211/41, 26, 126; 174/50, 52 R; 200/5 R, 5 A, 6 R, 6 A; 235/375; 364/708

CLAIM

The ornamental design for a computer, as shown.

DESCRIPTION

FIG. 1 is a top, front, right side perspective view of the computer showing my new design;

FIG. 2 is a front elevational view thereof;

FIG. 3 is a rear elevational view thereof;

FIG. 4 is a top, plan view thereof;

FIG. 5 is a bottom, plan view thereof;

FIG. 6 is a right side elevational view thereof; and

FIG. 7 is a left side elevational view thereof.

FIG. 1

FIG. 3

FIG. 4

FIG. 5

FIG. 6

FIG. 7
